ELMER L. SMITH AND ARTHUR E. PHELON, OF SPRINGFIELD, MASSACHUSETTS,
ASSIGNORS TO PACKAGE MACHINERY COMPANY, OF SPRINGFIELD, MASSA-
CHUSETTS, A CORPORATION OF MASSACHUSETTS.

WRAPPING-MACHINE.

1,313,864.

Specification of Letters Patent. Patented Aug. 19, 1919.

Application filed February 24, 1919. Serial No. 278,889.

To all whom it may concern:

Be it known that we, ELMER L. SMITH and ARTHUR E. PHELON, citizens of the United States of America, residing at 5 Springfield, in the county of Hampden and State of Massachusetts, have invented certain new and useful Improvements in Wrapping-Machines, of which the following is a specification.

10 Our invention relates to improvements in wrapping machines, and, in its present embodiment, relates specifically to machines for wrapping bars of chocolate, having one flat and one curved side, which are inclosed 15 in an inner wrapper and an outer label, although it will be understood that it is not limited to machines designed for use with such bars.

One object of our invention is to improve 20 the mechanism for transporting the articles through the machine, and to simplify the movement of such mechanism.

Another object is to improve the mechanism for making the end fold on the inner 25 wrapper.

Another object is to improve the means for making the final fold in the outer label.

In the drawings, in which like numerals indicate like parts throughout,

30 Figure 1 is a side elevation of the machine.

Fig. 2 is a plan view of the machine with some parts removed, taken on the line 2—2 of Fig. 1.

35 Fig. 3 is an elevation of the end folders for the inner wrapper, taken on line 3—3 of Fig. 1.

Fig. 4 is a similar view showing the chute and article elevated between the folding fingers.

40 Fig. 5 is a plan of the lower half of the chute under the end folding mechanism, showing the elevating device, taken on line 5—5 of Fig. 3.

45 Fig. 6 is a perspective view of the article and inner wrapper as they are delivered into the first tumble box.

Fig. 7 is a similar view showing the article and wrapper as they are ejected from 50 the first tumble box.

Fig. 8 is a view showing the preliminary action of the end folding fingers.

Fig. 9 is a view of the article after such action has taken place.

Fig. 10 is a bottom perspective view of 55 the article with the inner wrapper completely folded around it.

Fig. 11 is a side elevation of the second tumble box, the gluing device for the outer label, and the chute for receiving articles 60 from the second tumble box, taken on line 11—11 of Fig. 2.

Fig. 12 is a detail of the parts shown in Fig. 11 showing the article and outer label as they are about to be ejected from the 65 second tumble box.

Fig. 13 is a similar detail showing a further step in the ejection.

Figs. 14, 15, and 16 are views showing successive stages in the wrapping of the 70 outer label around the article, and

Fig. 17 is a section on line 17—17 of Fig. 2, showing the guide for preventing rotative movement of the reciprocating feeding arms. 75

This machine pushes a bar of chocolate or other article *a* into a sheet of paper *w* placed across a chute, forming a fold as shown in Fig. 6, and carries the two into a tumble box. The rotation of this tumble 80 box and the subsequent ejection of the article from it folds the paper as shown in Fig. 7. On ejection from this tumble box the article is located in a portion of a chute which is bodily movable vertically. The up- 85 ward movement of this chute carries the article and wrapper (Fig. 7) between end folders formed (Fig. 8) to give a preliminary fold and crease to the tubular end extensions of the wrapper, leaving them in 90 the condition illustrated in Fig. 9. A slight further upward motion of the chute causes the folders to tilt under the article (Fig. 4) and an elastic band to be drawn taut over the top of the article thus tensioning the 95 wrapper and folding its ends snugly under the article (Fig. 10). The chute then descends to its original position, and the article is fed into a second tumble box, picking up an outer label *z* on the way (Figs. 100 14 and 15). This label does not extend over the ends of the article, and by gumming the extending flap (Fig. 11) and by folding that flap onto the bottom of the article (Figs. 12, 13 and 16) the wrapping 105 is completed and the article may be ejected in any convenient manner. The mechanism operating on the article in its passage

through the machine will now be considered in order.

The articles *a* are fed into the machine along ways 10 by gravity or any suitable feeding devices, not essential to our invention, to a position between plates 11 and in front of a feeding arm 12. This arm, as well as arms 13, 14 and 15, is rigidly attached to a sliding bar 16 mounted for reciprocation in bearings 17 secured to the table 18 on which the mechanism is mounted. To prevent any movement of rotation by bar 16 and the feeding arms attached thereto, a depending member 19 (Fig. 17) is secured to it and has a projection 20 running in a slot 21 in a plate on table 18. Reciprocating axial motion is imparted to bar 16 and the feeding arms by cam 22 and connecting means comprising bell-crank 23, pivoted to the frame of the machine and carrying cam roll 24, and link 25, which as shown is in the form of a turnbuckle for adjusting the position of the feeding arms. It will be noted that all the feeding arms are in line with each other and are given only a simple back and forth motion in a single plane.

The article is pushed by the forward motion of arm 12 past a paper slot 26, between plates 27 similar to plates 11, and into a pocket formed by parallel spring pressed plates 28 mounted at one end on the hub 29 of the first tumble box. Paper is fed into slot 26 by any suitable device for feeding sheets or for cutting sheets from a web. Such devices are old and well known, form no part of our invention, and need not be illustrated nor described. By the sequence of operations just described the inner wrapper *w* is picked up as the article is pushed past slot 26, and as the motion is continued, the sides of the wrapper are folded about the article as shown in Fig. 6 by the action of plates 27.

The tumble box is of peculiar construction, having two pairs of plates forming two pockets separated by a space wide enough to receive feeding arm 13, as shown in Figs. 1 and 2. It is rotated from shaft 30 through a gear train comprising bevel wheels 31 and 32, pinion 33, and gear 34, the last of which is mounted on shaft 30. The second tumble box, to be described later, is mounted on the shaft of pinion 33. Intermittent rotation is imparted to shaft 30 by a Geneva movement of the usual form, having a slotted wheel 35 on shaft 30 and a crank 36 on a shaft 37 carrying cam 22 previously referred to. Shaft 37 receives continuous rotation from shaft 38 on which a driving pulley 39 is located, by means of chain 40 and sprockets 41 and 42. The intermittent rotary motion given to the tumble boxes, both of which are exactly alike, is sufficient to rotate them through 180° and then hold them

stationary long enough for the introduction of one article and the expulsion of another.

The structure of the tumble boxes cooperates with the feeding arms in a manner which avoids the necessity of stopping the tumble box while the feeding arm is returning to position after having ejected the article, and also admits of the feeding arms having a purely straight line motion. What may be termed the normal or original position of feeding arm 13 is that shown in Figs. 1 and 2, midway between the pockets of the tumble box. In this position the tumble box can rotate around it undisturbed. When the tumble box has stopped in the position shown, arm 13 moves to the left (Fig. 1) until it reaches the position shown in that figure as occupied by arm 14, thus expelling the article from the tumble box and locating it in position for the end folds to be made as will be described later. It then retraces its path toward the original position. While the feeding arm is so moving, however, the tumble box has commenced a rotation of 180°, and when the feeding arm reaches the tumble box on its return journey the tumble box has rotated through approximately 90°, so that the feeding arm can pass through the space between the two pockets without interference. It will be understood that the co-operation of arm 15 with the second tumble box is the same as that just described for arm 13 and the first tumble box.

By the rotation of the first tumble box the trailing flap *b* of the wrapper has been folded over as is common in machines of this type, so that when the article and wrapper are ejected from the tumble box it will be folded down as shown in Fig. 7. To assist in folding down and guiding this trailing flap a curved plate 43 may be mounted to partially encircle the tumble box (Fig. 1) in any convenient manner.

On ejection from the first tumble box the article, with the wrapper folded in tubular form around it, passes through a channel or chute whose bottom is formed by a stationary plate 44 and whose top by movable plates 45 carried on spring pressed pins slideable through arms 46. These arms are fastened to a head 47 carried on rods 48 passing freely through guides 49 secured to the table. Vertical reciprocation is given to the head by a rod 50 pivoted at one end to a depending ear 51 of the head and at the other to a lever 52 having a cam roll 53 running in a groove on a face cam 54 on shaft 38 (Fig. 1). Also secured to head 47 is an arm 55 supporting a plate 56 serving as a movable support for the article to raise it between the end folders as will be described. The article and wrapper are pushed from the first tumble box by arm 13 to a position directly on plate 58, head 47 being at that time in its lowered position. The head is then elevated

through the action of cam 54, carrying with it plates 45 and 56, and bringing the article between the end folders as shown in Fig. 4. The head is then lowered to its original position.

The end folders, shown in detail in Figs. 3 and 4, are carried on a cross piece 57 fastened to longitudinal members 58 mounted on posts 59 rising from the table 18. Attached to cross piece 57 by rods 60 is a head 61 having depending bearings 62 for the pivots of the end folders. These folders comprise plates 63 mounted on small blocks having arms 64 to which rods 65 are pivoted, the arms in turn being pivoted to a cross head 66. Projecting from this cross head is an arm 67 in the path of an adjustable stud 68 on one arm 46. By this means as head 47 is raised, bringing the article and wrapper between the folders, stud 68 contacts with arm 67 and head 66 is also raised, swinging the plates 63 on their axes through the medium of rods 65 and arms 64. A band of flexible material 69, preferably elastic fabric, is fastened at each end to folders 63.

The operation of the end folding devices is as follows, reference being had to Figs. 3, 4, 8, 9 and 10. Starting with the parts 30 in the position of Fig. 3, the article and wrapper having been placed on plate 56 by feeding arm 13, the movable portion of the chute, comprising plates 45 and 56, is raised. The first effect of this is to bring the projecting tubular ends of the wrapper between plates 63, which are in the position shown in Figs. 3, and 8. These plates have cut-away portions 70 having slanting sides, and as the wrapper passes up between them the 40 sides of the tubular extensions are turned in and the extensions themselves are bent down, forming a preliminary fold as shown in Figs. 8 and 9. At this instant stud 68 contacts with arm 67 and the folders are 45 tilted inwardly as shown in Fig. 4, bending the depending part of the wrapper under the article and tensioning the flexible strip 69 over the top of the article, thus drawing the wrapper taut. As the article descends, 50 the underlying folds are held in place by spring pressed pads 71 pivoted to arm 55 just below plate 56. These pads are yieldable so as to be pressed down out of the way by the end folders, but follow up as 55 the latter withdraw before the wrapper extensions have time to bend away from their folded position.

When the article, with the inner wrapper completely folded, has descended to the level 60 of the main part of the chute it is pushed by feeding arm 14 over a plate 72 and under plates 45 past a paper slot 73, where a label α , fed therein by any suitable means, is picked up as shown in Figs. 14 and 15; and 65 into one pocket of the second tumble box,

which has two spaced pockets formed by spring pressed plates 74 similar to plates 28 of the first tumble box. In the meantime feeding arm 13 has positioned another article under the end folders and, as the 70 feeding arms start their retrograde movement, the portion of the chute carrying the article has started to rise, so that when arm 14 approaches plate 56 and the article they have risen clear of its path. 75

The label is positioned in the paper slot 73 so as to provide one long trailing end c , which receives a stripe of glue and is folded on to the shorter end d on the flat side of the article. The gumming is done by the 80 customary oscillating glue pot 75 having a roll 76 and receiving motion from a cam on shaft 37 through bell crank 77, member 78 which is slotted to receive shaft 37, and cam roll 79 carried on member 78. The 85 glue pot descends after the tumble box has made its rotation and positions flap c as shown in Fig. 11, but before the ejection of the article is begun.

Trouble has been experienced in machines 90 of this character from two causes. First, it is necessary to have sufficient clearance for the flap c when the tumble box is in the ejecting position, so that the flap will of its own stiffness be presented to the glue 95 roll. Although intended to show details of the present machine Figs. 11 and 12 illustrate this point. In Fig. 11 there is enough clearance for the flap so that it extends straight from the article to the glue roll. 100 In Fig. 12 the end of the discharge chute is so close to the tumble box that the flap is forced to extend vertically, and could only be presented to the glue roll by additional mechanism. In the second place, if the end 105 of the discharge chute is spaced sufficiently from the tumble box to give this clearance, difficulty is found in making a tight fold. In the travel of the article from the tumble box to the delivery chute it passes through 110 this clearance space, during which time one surface of the article is unconfined. This gives opportunity to the folds to loosen, and a poor product results.

Our invention solves both of these problems, as will appear. The lower wall 80 of the delivery chute is fixed except for its customary spring mounting, but the upper wall 81 is pivoted to oscillate about a center 82. This action is obtained from a cam on 115 shaft 37 by lever 83 carrying a cam roll 84, link 85, and a lever 86 connected to the wall 81. When the tumble box first arrives in its ejection position the upper wall of the delivery chute is rocked into the position of 120 Fig. 11, affording free space for the extending flap c to present itself below the glue roll. After the gluing operation is completed wall 81 is raised into the position of 125 Figs. 12 and 18, thus folding flap c into a 130

vertical position, and the article is then ejected. As is apparent from Figs. 12 and 13, a practically continuously confined path is offered to the article, and there is no chance for the wrapper to loosen. It will also be seen that wall 81 serves three purposes—it presents the flap *c* to the glue roll, it folds this flap into a vertical position, and it serves as an abutment past which the article is pushed to make the final fold in the wrapper.

In order to prevent gumming of the mechanism if through some mischance no label is in position when the glue pot descends, the flap *c* is supported during the gluing operation by projections 87 and 88 carried on the upper wall 81. If no label is present the glue roll will descend harmlessly between the two projections, but if a label is present, its rigidity will be sufficient to insure gumming.

The articles may be ejected from the machine along guides 89 in any suitable way, either by pressure of the succeeding articles or by some well known conveying means forming no part of our invention, operated, for example, from shaft 90 which is driven intermittently through gears 34, 91 and 92 from shaft 30.

30 We claim:—

1. In a wrapping machine, a chute to receive a partially wrapped article, folding means adjacent the chute, and means for moving a portion of the chute and the article into the folding means.

2. In a wrapping machine, a chute comprising upper and lower plates and adapted to receive an article with a wrapper associated therewith, folding means adjacent the chute, and means for moving a portion of the chute including part of both the upper and the lower plates, together with the article, into the folding means.

3. In a wrapping machine, a path along which a partially wrapped article is adapted to travel, folding means located above such path, means for elevating the article from the path into the folding means, and means actuated by the elevating means for operating the folding means.

4. In a wrapping machine, a path along which a partially wrapped article may be moved, folding means adjacent the path, means for temporarily transferring the article from the path to the folding means, and means actuated by the transferring means for operating the folding means.

5. In a wrapping machine, a chute to receive a partially wrapped article, means for elevating a portion of the chute and the article above the line of the chute and for lowering them again into the line of the chute, and folding means operated by the elevating means to fold a portion of the wrapper while the article is elevated.

6. In a wrapping machine, a chute to receive a partially wrapped article, pivoted end folders located adjacent the chute, means for moving a portion of the chute and the article between the end folders and moving them back again into the line of the chute, and means actuated by the motion of the chute for swinging the end folders to fold a portion of the wrapper.

7. In a wrapping machine, a chute to receive a partially wrapped article, pivoted end folders located above the chute, means for elevating a portion of the chute and the article between the end folders and lowering them again into the line of the chute, and means actuated by the elevation of the chute for swinging the end folders to fold a portion of the wrapper.

8. In a wrapping machine, a chute adapted to receive a partially wrapped article; end folders located above the chute; means for elevating a portion of the chute and the article between the end folders, whereby the ends of the wrapper are given an initial fold; means operated by a further elevation of the chute to swing the end folders to fold the ends of the wrapper under the article; and means operable after the return of the said portion of the chute and the article to their original position to move the article along the chute.

9. In a wrapping machine, a path along which a partially wrapped article is adapted to travel, folding means adjacent such path, means for tensioning the wrapper about the article, means for transferring the article from the path into the folding means, and means actuated by the transferring means for operating the folding and tensioning means.

10. In a wrapping machine, a path along which a partially wrapped article is adapted to travel, folding means located above such path, means for tensioning the wrapper about the article, means for elevating the article from the path into the folding means, and means actuated by the elevating means for operating the folding and tensioning means.

11. In a wrapping machine, a chute to receive partially wrapped articles, a tumble box in the line of the chute having spaced article receiving pockets, means for rotating the tumble box, and ejecting means for the article movable through one of the pockets to eject an article therefrom and movable back to its original position through the space between the pockets when the tumble box has rotated from the ejecting position.

12. In a wrapping machine, folding means, a chute adapted to receive a partially wrapped article and having a portion thereof movable transversely from a position adjacent the folding means to a position where the article may be acted upon

by the folding means, and reciprocating means for feeding the article along the chute movable through the chute to feed the article and movable back to its original 5 position when the said portion of the chute is in the folding position.

13. In a wrapping machine, in combination, a chute to receive partially wrapped articles, a tumble box in the line of the 10 chute, and a plurality of reciprocating members always movable in a straight path and in line with each other for feeding the articles along the chute and through the tumble box.

15 14. In a wrapping machine, a chute, a plurality of reciprocating means always movable in a straight path and in line with each other for feeding a plurality of articles along the chute in one direction, means for 20 folding a wrapper about the article, and means associated with the folding means for temporarily removing the articles from the path of the reciprocating means during the retrograde movement of the latter.

25 15. In a wrapping machine, a tumble box constructed and arranged to receive a partially wrapped article with one extending flap, a chute adjacent the tumble box having one movable wall, and means for moving 30 such wall between a position out of the path of the said extending flap and a position to receive the article ejected from the tumble box.

35 16. In a wrapping machine, a tumble box constructed and arranged to receive a partially wrapped article with one extending flap, means for gluing such flap, means to

eject the article from the tumble box, means to receive the article so ejected, and means to move said receiving means so that it will 40 not interfere with the presentation of the flap to the gluing means.

17. In a wrapping machine, a tumble box constructed and arranged to receive a partially wrapped article with one extending 45 flap, an oscillating glue roll, a chute adjacent the tumble box having one movable wall, and means for moving that wall between a position presenting said flap to the glue roll and a position to receive an article 50 ejected from the tumble box.

18. In a wrapping machine, gluing means, folding means, and means for moving said folding means to a position in which it presents a wrapper flap to the gluing means 55 and then moving it to fold the flap.

19. In a wrapping machine, a tumble box constructed and arranged to receive a partially wrapped article with one extending flap, means to apply glue to that flap, folding means for that flap, and means moving the folding means first to present the flap 60 to the gluing means and then to fold it.

20. In a wrapping machine, an abutment past which an article and wrapper are 65 moved to fold a flap of the wrapper, means to present the article to the abutment and to move the article past it to fold the flap, and means acting prior to the folding operation to move the abutment from an inoperative position to a position where it may 70 receive the article so presented.

ELMER L. SMITH.
ARTHUR E. PHELON.
